UNITED STATES PATENT OFFICE.

DAVID E. G. CLARKE, OF NEW YORK, N. Y.

WASHING-MACHINE.

1,077,330.

Specification of Letters Patent.

Patented Nov. 4, 1913.

Application filed January 6, 1913. Serial No. 740,500.

To all whom it may concern:

Be it known that I, DAVID E. G. CLARKE, a subject of the King of Great Britain, and resident of the city of New York, in the county of New York and State of New York, have invented certain new and useful Improvements in Washing-Machines, of which the following is a specification.

The present invention relates to washing machines, and has for one of its objects to provide a device in the form of a closed receptacle, in which a circulation of water or other suitably prepared liquid, either hot or cold, is induced which will cleanse or wash the clothes or fabrics therein without subjecting the same to the usual pounding or rubbing.

Another object of the invention is to provide a device of this type which serves at the same time for rinsing the clothes or fabrics, and also for drying same.

With these and other objects in view, which will more fully appear as the nature of the invention is better understood, the same consists in the combination, arrangement and construction of parts hereinafter fully described, pointed out in the appended claims and illustrated in the accompanying drawings, it being understood that many changes may be made in the size and proportion of the several parts and details of construction within the scope of the appended claims without departing from the spirit or sacrificing any of the advantages of the invention.

One of the many possible embodiments of the invention is illustrated in the accompanying drawings, in which:—

Figure 1 is a vertical section taken through an apparatus constructed in accordance with the invention, partly in elevation; Fig. 2 is a plan view thereof; Fig. 3 is a section taken on line 3—3 of Fig. 1; and Fig. 4 is a side elevation of the lower part of the apparatus.

In the drawings, the numeral 10 indicates a wash-boiler of any suitable material, and preferably of cylindrical shape, although it will be easily seen that it may be of any other configuration. In this boiler is centrally arranged a receptacle 11, also cylindrical, provided in its cylindrical wall with a plurality of perforations 12, 12. To the bottom 13 of this receptacle is attached a flange 14, with which is made integral a vertical spindle 15, the latter projecting

through an opening 17 in the bottom 18 of the boiler. Obviously some means must be employed which prevent the leakage of the water through the opening 17. Longitudinal grooves 19 are provided throughout the height of the boiler 10, and in these grooves are placed packing strips 20, which contact with the outer face of the receptacle 11, and thereby divide the annular space, formed between the boiler and receptacle, into two compartments 21 and 22. A packing ring 20', held upon the boiler in any suitable manner, closes the upper end of said annular space.

To the bottom 13 of the receptacle 11 is centrally fastened an upwardly extending screw threaded spindle 23, which projects through an aperture 24 in a cover 25, which snugly fits the receptacle 11, said cover being provided with a handle 26. The screw threads of the spindle 23 mesh with a wing-nut 27, for a purpose hereinafter to be described.

To the underface of the cover 25 is centrally secured a perforated tubular member 28, the flange 29 of which engages the flange 30 of a perforated tubular member 31, adapted to slide into a perforated tubular member 34, the latter being attached to the bottom of the receptacle 11. These tubular members are adapted to telescope.

The boiler 10 has upon diametrically opposite portions perforations 35 and 36, through which the compartments 21 and 22 communicate with chambers 37 and 38, respectively, which are formed upon the boiler. In the chamber 37 is located an electric heater 39 of any suitable construction, the wires leading thereto being denoted by the numerals 40, 40. Circulation of the liquid is maintained in the apparatus by suitable means, for instance a centrifugal pump 41, the discharge end of which is connected by a pipe 42 with the top of the chamber 37, while its suction inlet communicates through a pipe 43 with the bottom of the chamber 38. A three-way valve 44 is inserted into the pipe 42 for a purpose hereinafter to be described. Rotation is imparted to the centrifugal pump by means of a suitable prime mover, for instance an electric motor 45, the shaft of which is coupled with the impeller shaft of the centrifugal pump.

The motor imparts at the same time rotation to the spindle 15 above referred to. Any suitable power transmitting apparatus may

be employed, for instance bevel gears, one of the same, denoted by the numeral 46, being keyed to the motor shaft and in mesh with another gear 47, which is fixedly attached to the spindle 15.

The operation of the device is as follows: The cover 25 is removed from the washing machine, the clothes or fabrics to be washed placed into the receptacle 11, the usual amount of liquid put into the receptacle, after which the cover is put into place and the nut 27 screwed up until the cover rests on the wash to prevent steam, which might be generated in the boiler, from blowing off the cover. Current is then supplied to the electric heater and the three-way valve 44 set to open a communication between the chamber 37 and the centrifugal pump. The motor 45 is put in operation, whereby the receptacle 11, containing the wash, is rotated, and the liquid caused to circulate through the boiler and the receptacle. The liquid entering the chamber 37 is heated therein, flows into the boiler through the perforations 35, and passes thence through the perforations 12 into the receptacle and through the clothes or fabrics. Due to the suction generated in the chamber 38, the liquid flows into this chamber and thence to the pump, to follow again the cycle described. A forced circulation of the liquid is thus obtained which will perform a cleansing operation. It will be observed that, since the receptacle 11 rotates, the liquid from the chamber 37 will in succession come into contact with all of the clothes and thus cleanse the same thoroughly. The annular space between the boiler and the receptacle is divided into two compartments in order to retard the flow of the liquid. The centrally arranged tubular members 28, 31 and 34 form a space which does not contain wash and serves to direct the flow of the liquid, the latter flowing through the said tubular members, due to the fact that there the least resistance is offered to the same. From these tubular members it flows, due to the suction, toward the chamber 38. After the clothes or fabrics have been thoroughly washed, the three-way valve 44 is set to close the communication between the pump and the chamber 37. By continuing the operation of the pump, the water is removed from the washing machine and flows into a receptacle placed beneath the three-way valve. A fresh supply of water is then put into the washing machine and the operation now described repeated, whereby the clothes or fabrics will be thoroughly rinsed. After the rinsing operation, the water is drawn off and the suction of the pump maintained for a considerable time, whereby the machine is drained and the clothes or fabrics

to some extent dried. By turning the three-way valve 44 again to a position in which a communication is established between the pump and the chamber 37 and keeping the heating device in operation, the centrifugal pump will cause a circulation of hot air through the washing machine, which will thoroughly dry the wash therein.

It is to be noted that instead of making use of a motor for actuating the pump and rotating the receptacle, hand power may be employed.

What I claim is:—

1. In an apparatus of the character described, the combination with a closed cylindrical tank, of a perforated cylindrical receptacle rotatably arranged therein adapted to receive a liquid and the articles to be treated, the annular space formed between said tank and said receptacle being divided into two compartments, a cover upon said receptacle, a pump drawing liquid from one of said compartments and forcing it into the other one, and means for rotating said receptacle and its contents.

2. In an apparatus of the character described, the combination with a closed cylindrical tank, of a perforated cylindrical receptacle rotatably arranged therein adapted to receive a liquid and the articles to be treated, the annular space formed between said tank and said receptacle being divided into two compartments, a cover upon said receptacle, a pump drawing liquid from one of said compartments and forcing it into the other one, means for rotating said receptacle and its contents, and a perforated tubular member centrally arranged within said receptacle.

3. In an apparatus of the character described, the combination with a closed cylindrical tank, of a perforated cylindrical receptacle rotatably arranged therein adapted to receive a liquid and the articles to be treated, the annular space formed between said tank and said receptacle being divided into two compartments, a cover slidably arranged upon said receptacle, a pump drawing liquid from one of said compartments and forcing it into the other one, means for rotating said receptacle and its contents, and a plurality of telescoping perforated tubular members centrally arranged within said receptacle extending from said cover to the bottom of said receptacle.

Signed at New York, in the county of New York and State of New York, this 31st day of December, A. D. 1912.

DAVID E. G. CLARKE.
